Primary Examiner — Kevin K Rudzinski*Assistant Examiner* — Paul D Bohannon(57) **CLAIM**

The ornamental design for outdoor kitchen cabinet doors, as shown and described.

DESCRIPTION

FIG. 1 is a front elevational view of outdoor kitchen cabinet doors;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a top perspective view thereof;

FIG. 8 is a bottom-front-right perspective view thereof;

FIG. 9 is a bottom-front-left perspective view thereof;

FIG. 10 is a bottom-rear-left perspective view thereof; and,

FIG. 11 is a bottom-rear-right perspective view thereof.

The broken line showing of a counter top and counter base is included for the purpose of illustrating environmental structure and forms no part of the claimed design.
